UNITED STATES PATENT OFFICE

96,783

DESIGN FOR A HOT POT HOLDER

Helen I. Snyder, Chicago, Ill.

Application May 17, 1935, Serial No. 56,887

Term of patent 7 years

To all whom it may concern:

Be it known that I, Helen I. Snyder, a citizen of the United States, residing at Chicago, in the county of Cook and State of Illinois, have invented a new, original, and ornamental Design for a Hot Pot Holder, of which the following is a specification, reference being had to the accompanying drawing, forming part thereof.

Figures 1, 2 and 3 are respectively front, rear and side elevational views of a hot pot holder, showing my new design.

I claim:

The ornamental design for a hot pot holder, as shown.

In testimony whereof I affix my signature.

HELEN I. SNYDER.
